UNITED STATES PATENT OFFICE

2,421,877

SUCTION ATTACHMENT

Bernard Gross, San Diego, Calif., assignor to
 Rohr Aircraft Corporation, Chula Vista, Calif.,
 a corporation of California

Application August 27, 1945, Serial No. 612,895

7 Claims. (Cl. 230—114)

1

My invention relates to suction attachments, and its objects are to provide a more effective means for quickly removing gases and volatile liquids from tanks, chambers, compartments, vessels or the like, prior to inspection, renewed use or repair thereof; to accelerate the volatilization of liquids entrapped by hat beams, stringers or other abutments normally present in airplane wing tanks or similar hollow constructions; to furnish a suction means for the ready removal of vapors from tanks or receptacles, which admits of a wide range of maximum and minimum adjustment, and to provide a simple suction attachment which can readily and economically be applied to blowers of conventional type and greatly increase their efficiency at a substantially reduced cost of operation. Other objects will appear from the drawing and as hereinafter set forth and described.

The removal of residual gasoline from tanks, prior to inspection and repair has been accomplished by several means in the past. Sometimes a stream of air is permitted to pass into one of the orifices of the tank to remove vapors by causing a change of air. Tanks are sometimes purged with carbon dioxide. The carbon dioxide gas is permitted to flow into the tank at an orifice which is located at its lowest point. Carbon dioxide, being heavier than the mixture of gasoline vapors and air, will remain in the lowest areas of the tank. As more carbon dioxide is permitted to enter the tank it moves up toward the top of the tank and in so doing, replaces gasoline vapors and air. This continues until carbon dioxide finally passes out of the top orifices of the tank.

Also after the interior of a fuel tank has been treated through the application of sealing materials to the walls thereof to repair or leakproof the same, the problem is presented of getting the tank ready for the reception of fuel unimpaired by vapors or liquids left behind by said fluids. The vapors from volatile liquids used in sealing fuel tanks, airplane wing floats, airplane pressure cabins and the like must be quickly and effectively removed after the sealing process or sealing repair procedures. The removal of these volatile materials presents similar problems as the removal of gasoline vapors from fuel tanks do.

In the case of integrally built tanks and other structures in which various types of beams and joints are involved, these two common methods are unsuitable because they are not effective enough and require too much time. Therefore, it has become desirable to provide a more rapid

2

and effective means of removing vapors from tanks, compartments and the like. My improved attachment has accordingly been devised as a satisfactory means of solving these problems.

5 My invention primarily consists in an assembly of telescoping tubes constructed to be connected at one end with the orifice of a tank and to be adjustably separated at the other end by a gap from the induction end of suction apparatus, the 10 diameter of such adjacent ends being such as to secure upon adjustment of width of said gap, a range between the maximum and minimum suction results of which such suction apparatus is capable.

15 My invention further consists in other improvements, novel features of construction, combination and arrangement of parts, illustrated in the drawing and more particularly hereinafter described and claimed.

20 Reference is hereby made to the drawing, illustrating a preferred form of my invention, in which similar numerals of designation refer to similar parts throughout the several views, and in which,

25 Figure 1 is a side elevation of my suction attachment and conventional blower to which the same is secured, showing the mounting thereof upon a conventional tank and connection thereof to an orifice or outlet of said tank for the purpose of removing vapors therefrom;

30 Fig. 2 is a longitudinal section of the apparatus and connections shown in Fig. 1, with certain parts removed for the purpose of clearness, and

Fig. 3 is a section on line 3—3 of Fig. 1 looking in the direction of the arrows.

35 Referring to the drawing, my improved attachment 4 comprises the main tubular member 5, having downwardly extending from the outer end thereof, the neck 6 in telescopic connection with the flanged inlet mouthpiece 7, and having at its inner end, and telescoping therewith, the sliding tubular nozzle 8. Upwardly extending from said outer end of the tubular member 5, and preferably integral therewith, is the fin 9, connected by the arm 10 and braces 11 to the wall of the screened mouthpiece of the inlet end of suction funnel 12 of the conventional blower 13; the said arm and braces serving through the said fin to support the member 5 in operative position in respect to said blower, with the gap 20 therebetween. As shown

40 in the drawing, the main structure of the blower 13 is provided with legs 14 resting on the top of the tank 15; and the telescoping flanged mouthpiece 7 is protruded from the neck 6 to register with the orifice outlet 16 of such tank; a washer 45 17 of rubber or other suitable material being

interposed between the flange of said mouthpiece 7 and wall of the tank to secure cushioning sealed connection thereof. A pressure gage 18 is conveniently mounted upon the blower 13 and is connected by a flexible tube 19 to the member 5 of my suction attachment.

The diameter of the passageway of the tubular nozzle 8 of my suction attachment in relation to the diameter of the inlet end or suction funnel 12 of the blower 13 is made to conform with the result of tests made to determine the greatest amount of suction when the end of such nozzle is set against the screened end of said funnel; and the width of the gap 20 may be varied upon extension or retraction of the telescoping nozzle 8 as occasion requires, the degree of such width being determined through the use of the pressure gage 18 as greater or less suction is desired. When the ends of the said nozzle and inlet end or funnel are so in contact the maximum suction of the blower is exerted, and as they are moved apart such suction diminishes to zero at the greatest width of the gap 20; so that degrees of adjustment of the amount of suction can readily be brought about and in a manner never heretofore accomplished in the art. As will be observed from Fig. 2, the diameter of the end of nozzle 8 is somewhat smaller than the mouth of the funnel, so as to leave an annular space therebetween when they are in contact, through which space outside air may be drawn into the blower in addition to that coming from the tank.

When my improved attachment is employed for the removal of gases in connection with a conventional suction blower as shown, it is installed preferably upon the top of a tank or other vessel, and the mouthpiece 7 brought in registration with the orifice outlet of such tank and pressed down and sealed thereon. The sliding nozzle 8 is thereupon extended or retracted upon the member 5 to obtain the desired amount of suction for the removal of fuel vapors or volatile solvents remaining within such tank; the pressure gage 18 being used as above described in determining such adjustments. In this connection, I have discovered that my new equipment permits the high volume suction capacity at the suction levels required for the removal of said vapors and solvents; such suction, however, not being great enough to collapse or harm by excess flexing the conventional types of airplanes or other constructions embodying tanks, chambers, cabins, compartments or the like. Whereas, it formerly took up to 24 hours with other types of equipment to remove vapors in certain types of integrally built tanks and compartments, it is now possible to remove residual volatile liquids and vapors in a matter of minutes. This is so because the high volume capacity suction unit permits the rapid boiling off of residual volatile liquids even when an orifice toward the bottom of the tank is open. In such a case, it is possible to obtain a constant drop in pressure as well as a change in air with this equipment. The former use of air pressure retards the volatilization of liquids entrapped in tanks and compartments made of hat beams, stringers, and the like in airplanes, and due to the fact that complete liquid drainage is impossible in this type of tank. Carbon dioxide purging is ineffective because only vapors which exist during the time of purging are removed. After purging, the entrapped liquid will volatilize and fresh vapors occur. Again, the use of air pressure in the tank will retard volatilization while suction will accelerate volatilization

of entrapped liquids. This attachment can be applied to blowers of conventional type.

Where in the appended claims I employ the word "tank," I desire to be understood as including any tank, chamber, compartment, vessel or the like in which may be confined or contained the gases or volatile liquids the removal whereof is to be effected through the use of my invention.

My invention may be embodied in other specific forms without departing from the spirit or essential characteristics thereof. The present embodiment, as above set forth, is therefore to be considered in all respects as illustrative and not restrictive, the scope of my invention being indicated by the appended claims rather than by the above description, and all changes which come within the meaning and range of equivalency of the claims are therefore intended to be embraced therein.

What I claim and desire to secure by Letters Patent is:

1. In apparatus of the class described, the combination of a tank with an outlet opening, a blower with a suction inlet opening and a suction attachment aligned therewith, both mounted with gap therebetween upon said tank; said attachment comprising a main tubular member, a tubular neck connected with one end of said member and forming an inlet therein registering with the outlet opening of said tank, and a tubular outlet nozzle adjustably connected with the other end of said member and movable within said gap toward and from the suction inlet opening of said blower.
2. The subject matter of claim 1, including constructing the outlet nozzle of smaller diameter in respect to the diameter of the suction inlet opening of the blower, so as to form a space therebetween when the two are in contact, to aid in providing an influx of outside air in addition to the air drawn in from the tank.
3. In apparatus of the class described, the combination of a tank with an outlet opening, a blower with a suction inlet opening and a suction attachment aligned therewith, both said blower and attachment with a gap therebetween mounted upon said tank; said attachment comprising a main tubular member open at one end and closed at the other, a tubular neck connected with the closed end of said member and forming an inlet therein, the outer end of said neck registering with the outlet opening of said tank and being connected therewith, and a tubular outlet nozzle adjustably connected with the open end of said member and movable within said gap toward and from the suction inlet opening of said blower.
4. In apparatus of the class described, the combination of a tank with an outlet opening, a blower with suction opening and attachment aligned therewith each separately mounted upon said tank; said attachment comprising a main tubular member, open at one end and closed at the other, a tubular neck extending laterally from said member and forming an inlet therein, a tubular mouthpiece telescopically connected with said neck and registering with the outlet opening of said tank, and a tubular outlet nozzle telescopically connected with the open end of said member and in alignment with the suction opening of said blower.
5. In apparatus of the class described, the combination of a tank with an outlet opening, a blower with a suction inlet opening and a suction attachment aligned therewith each mounted

upon said tank; said suction attachment comprising a main tubular member, means for securing said member to the inlet end of said blower with a gap therebetween, a tubular neck connected with said member and forming an inlet therein registering with the opening of said tank, and a tubular outlet nozzle adjustably connected with, and opening out of, said member and extensible into and retractable out of said gap.

6. In apparatus of the class described, the combination of a tank with an outlet opening, a blower with an inlet opening, a cylindrical suction attachment secured to said blower and aligned therewith, both said blower and attachment being mounted upon said tank; said suction attachment comprising a main tubular member having its inner end normally separated from the inlet end of the blower by a gap therebetween, a tubular telescoping inlet neck connected with the outer end of said member and registering with the outlet opening of said tank; and a tubular outlet nozzle telescopically connected with said inner end of said member and slidably into and out of said gap.

7. In apparatus of the class described, the combination of a tank with an outlet opening, a blower with a suction inlet opening and a suction attachment aligned therewith each mounted upon said tank, the inlet end of said blower and

outlet end of said attachment being normally separated by a gap therebetween; said attachment comprising a main tubular member open at one end and closed at the other; a neck secured to said member and forming an inlet therein adjacent to its closed end and being removably connected to the outlet opening of said tank; and a tubular outlet nozzle adjustably connected to the open outlet end of said member and longitudinally extensible and retractable into and out of said gap to and from the inlet end of said blower; the diameters of the inlet end of the blower and tubular outlet nozzle not being the same and being such as to secure upon longitudinal adjustment of said nozzle a wide range of suction results within the said tank.
